[57] CLAIM

The ornamental design for a hoe, as shown.

DESCRIPTION

FIG. 1 is a side elevational view of a garden hoe showing my new design with the opposite side being a mirror image thereof;

FIG. 2 is a front elevational view thereof;

FIG. 3 is a top plan view thereof;

FIG. 4 is an enlarged, fragmentary top plan view of the lower portion of the garden hoe;

FIG. 5 is an enlarged, fragmentary bottom plan view thereof;

FIG. 6 is an enlarged, fragmentary side elevational view thereof; and,

FIG. 7 is an enlarged, fragmentary rear elevational view thereof.

The hoe is partially shown in FIGS. 4-7 for ease of illustration.
